The ornamental design for a combined needle stopper and remover, as shown and described.

DESCRIPTION

FIG. 1 is a perspective view of a combined needle stopper and remover showing our new design;

FIG. 2 is a top plan view thereof;

FIG. 3 is a front side elevational view thereof;

FIG. 4 is a right side elevational view thereof;

FIG. 5 is a bottom plan view thereof; and,

FIG. 6 is a perspective view thereof, the broken line showing is for illustrative purposes only and forms no part of the claimed design.
